COMBINED POKER AND BRUSH FOR A GARBAGE DISPOSER

Jean N. Busse, 113 Windward Island,
Clearwater, Fla. 33515

Filed Oct. 13, 1969, Ser. No. 19,519

Term of patent 14 years

Int. Cl. D4—01

U.S. Cl. D4—6

Fig. 1

Fig. 2

Fig. 3

Fig. 4

FIG. 1 is a front elevation of the combined poker and brush for a garbage disposer of my present design.

FIG. 2 is a side elevation thereof.

FIG. 3 is a top plan view.

FIG. 4 is a bottom plan view.

The two sides not shown are substantially identical with FIGS. 1 and 2.

I claim:

The ornamental design for a combined poker and brush for a garbage disposer, as shown and described.
